UNITED STATES PATENT OFFICE

MELVIN E. HARTZLER, OF DOWNTERS GROVE, AND THOMAS H. FERGUSON, OF OAK PARK, ILLINOIS; SAID FERGUSON ASSIGNOR TO SAID HARTZLER

YIELDING UPRIGHT TRAFFIC MARKER

Application filed March 15, 1929. Serial No. 347,325.

The present invention relates to yielding upright traffic markers. In general these markers comprise, in each case, a panel of flexible resilient water-proof material adapted to be positioned in the path of vehicular travel. Normally the panel extends upward because of its resiliency, and displays some sort of indication to be observed by the approaching driver. The panel remains upright until it is encountered by the wheel of the oncoming vehicle. Then it is forced down flat on the pavement by the weight of the vehicle and remains so while the wheel is passing over it. As soon as freed the panel springs back to its normal upright indicating position.

In markers of this kind heretofore proposed, the engagement of any portion of the marker by the wheel of the vehicle bends the whole panel. Thus, no matter where the blow of the oncoming wheel is delivered, the panel is bent, theoretically at least, along its entire bending axis. Consequently every blow produces a maximum of bending wear. One object of the present invention is to avoid this bending wear throughout the length of the panel and to provide a structure wherein each blow bends at most only part of the entire indicating portion of the marker, thereby increasing the life of the marker.

Again in markers of the class described, the wear is likely to be excessive at one or more given points in the marker and when the marker is worn out at those points, it can only be put in proper repair by removing the entire blade or panel and replacing it by a new one. A second object of the present invention is to increase the life of the marker by a construction such that the parts that are excessively worn may be replaced without replacing the entire panel.

The prior art markers also require a flattening of the entire panel every time a wheel passes over the marker. Another object of the invention is to avoid this flattening every time a vehicle passes and to provide a construction where certain zones within the length of the marker will allow the passage of the wheels of a vehicle without flattening

out any portion of the upright indicating member.

In markers of this class heretofore in use, the rubber tires of the oncoming traffic strike a hard metal surface. This delivers a sharp blow to the tire in each instance. Another object of the invention is to reduce the hardness of these blows and thus prolong the life of the marker, obviously, also, reducing the wear on the tires. By constituting the forward edge of the marker base of resilient rubber, the blows delivered by the tires are cushioned and rendered less severe.

Other objects of the invention are to construct a marker of low cost, capable of being quickly and readily repaired, having readily interchangeable parts, one made up of parts that may be carried in stock and variously assembled to provide the composite marker and one which will be easily installed and when so installed will be efficient and durable under all the varying conditions of service.

In attaining these objects, we preferably make up the marker by assembling a member of sections or units, and construct each unit with a flexible upright leaf or blade rising from a thicker and more substantial base. The base remains fixed in place but the leaf flaps back and forth as the traffic passes over it. Preferably, too, the leaf in each instance is narrower as viewed by the oncoming driver than the base. Thus, spaces are left between the indicating leaves or units of an assembled marker and many wheels of the traffic pass through these spaces and do not depress the leaves at all.

In manufacturing these unitary sections we preferably provide an opening or bore through the base in a lengthwise direction, that is to say, in a direction to extend crosswise of the oncoming traffic. The sections or units are then assembled to make up the complete composite marker by threading a metal bar or rod through these openings. This bar serves as a core for the marker and by attaching the core to the pavement the entire assembled marker is held in place. Ordinarily, suitable anchor bolts secure the core bar to the pavement.

The sections may also be used alone. They

need not be combined at all times into a composite marker. In many instances the single sections may be strung along the pavement like the marker buttons now in common use and in many instances the markings may be placed on these paneled markers strung along the pavement so as to be read by the driver as he approaches, each section forming one letter or part of the full word or information to be conveyed by the string of single markers.

With these general observations we may now pass to a consideration of the fuller disclosure of the invention set forth in the following detailed description and accompanying drawing. The scope of the invention will be particularly pointed out in the appended claims.

In said drawing Fig. 1 is a perspective view of a marker constructed in accordance with the present invention; Fig. 2 is a similar view illustrating a modification wherein the upright portions are quite narrow; Fig. 3 is a similar view illustrating a modification wherein the upright portions have narrow supporting stems and broader faces for the lettering or other indicia to be placed thereon; Fig. 4 illustrates a modified section or unit wherein the base has the full width of the upper portion; Fig. 5 is a side elevation of one of the sections illustrated in Fig. 1; Fig. 6 is a plan view of the same; Fig. 7 is a side elevation illustrating a modification wherein the section of the marker is secured to a base plate which may be placed upon the surface of the pavement; Fig. 8 is a perspective view of a modified section of uniform width in association with a spacing section; and Fig. 9 is an elevation of the modified section of Fig. 8 showing in dotted lines how the upright panel bends down when driven over. Throughout these views like characters refer to like parts.

Referring to the drawing in detail, A designates the display sections, B the core upon which the display sections are threaded to build up the complete marker and C the pavement to which the marker is attached.

The sections A in each instance comprise a base portion 10 and an upright display portion 11. The display portion is in the form of a light flexible sheet which extends upward and may be readily flattened out upon the surface of the pavement, as illustrated in dotted lines in the case of the "P" section in Fig. 1. Each upright leaf is preferably integral with the base 10 and the entire section is made of rubber. The display portion 11 forms the back-ground of the letter or other indicating symbol 9 upon its face and preferably is black. The symbol upon the face of it is given a color which will have the best visibility under all circumstances of service. This is usually a

federal yellow, orange, or chrome orange. The designating character is molded at the same time that the entire section is molded and consequently is integral with the portion 11. The rubber constituting the upright portion 11, which may be referred to as a leaf, panel or blade, is a high grade resilient rubber which is capable, when made in the thin leaf-like form illustrated, of promptly resuming its upright position following each flattening by the blows of the traffic and of so acting continually for a long period of service.

If desired the interior of each section may be reinforced by a fabric applied during manufacture so as to lie near its surface. Such a fabric 12 preferably extends through base 10 and the upright portion 11 as shown in Fig. 4. This matter of reinforcement is one which may be employed or not as desired.

The base 10 as before stated is molded integral with the upright 11 and is likewise of rubber, reinforced or not, as desired. The upper surface of the base 10 is curved downward toward the oncoming traffic so as to provide a thin free edge 13 over which the traffic will pass without appreciable jolt and which will fit more or less closely irregularities in the surface of the pavement 95 C. The under surface 14 is flat so as to fit against the pavement. As shown, the base 10 has a longitudinal dimension greater than that of the panel 11. Preferably the panel is positioned centrally so that the projecting portions of the base at each end of it are equal. The rear portions of the ends of the base which extend beyond the upright 11 are curved downward so as to form a lip 15 similar to the lip 13. Because of the difference in the dimensions of the base 10 and the blade 11, spaces 16 are provided between adjacent panels 11. In service the wheels of a vehicle may often pass through these spaces without striking one of the panels. Thus a good deal of the traffic may pass over the base of the marker without flattening down the panels and thereby the life of the marker is prolonged. Likewise by having the marker divided into sections 110 an oncoming vehicle if it does not cause its wheels to pass through one of the spaces 16 will at most only flatten out one of the panels 11. This also contributes to the life of the marker.

The base 10 is preferably secured to a long core B and the latter in turn is secured to the pavement C by one or more anchor bolts 17. This core obviously may take different forms but it is preferably a 125 rolled steel bar. Preferably in forming the sections a mandril is used so as to mold the sections with a transverse opening 18 through the base. This opening is large enough to receive the bar B and conse- 130

5 quently when it comes to assembling the parts of the marker it is only necessary to slip the desired sections upon the core. Each base 10 is also preferably provided with an opening 19 through which one of the anchoring bolts 17 may be passed if desired. In such case the core B is also provided with an opening for the passage of the anchor bolt as clearly shown in Fig. 5.

10 By way of illustration it may be pointed out that in ordinary practice the tops of the sections A extend about seven inches above the pavement and the thickness of the base 10 at its center in such case would be

15 about three-fourths inch.

Obviously, both the base and display portions of the sections may be considerably varied and still come within the purview of the invention. Thus, as shown in Fig. 2, 20 the uprights 20 of the sections A' are quite narrow. Because of this, the spaces 21 between them are relatively wide and therefore the liability of the fingers being strucken down by the wheels of an approaching 25 vehicle is much less than would be the case were the fingers wider. Even though the fingers 20 are quite narrow still their forward faces may be large enough to provide for designating characters such as the letter 30 "O", designated 22, which requires three of the fingers to complete it. Even though the character is broken by the spaces yet it will be sufficiently clear to the driver of an oncoming vehicle. The sections A' in this 35 modification may be secured to the pavement as desired. A core B is shown extending through them just as in the case of the sections A, above considered. Here too there are the screw openings 19, heretofore described.

40 In Fig. 3 another modification is shown in which the sections A² are provided with uprights having cylinder stems 23 and flat faces 24. In this way the resiliency of the upright may be considerably increased by 45 reason of the slender resilient stems 23 and yet a wide face is provided for the lettering or other designations to be placed on the marker. In this instance the letter "U", 50 designated 25, is placed upon two of the faces 24 and the letter "S", designated 26, is also of such width as to require two of the faces 24. In this instance the segments A² 55 may be secured to the pavement as desired. They have the same core opening 18 and screw openings 19 as previously described.

60 Instead of attaching the various sections A or their modifications A¹ and A² to a long core B, it is clear that they might be individually secured to the pavement by anchor bolts as is commonly done with round markers, such as disclosed in M. E. Hartzler's prior application Serial No. 290,321, filed 65 July 5, 1928. In such case the core may be placed within the mold and molded directly

in the base of the section at the time it is manufactured. Such a construction is illustrated in Fig. 4. There the section A³ has the same lengthwise dimension throughout, that is, the same dimension lengthwise of 70 the marker and transverse to the direction of travel of the traffic, thus providing an indicating panel 29 and base 30 of the same width. The core 31 is a short piece of metal molded in the base 30 as illustrated. An 75 opening 32 through the base 30 including the core 31 provides for attaching the section to the pavement. The usual anchor bolt may be used for this purpose. In this case the entire section is shown provided 80 with the reinforcing fabric 12 previously mentioned. The upright of this section is also a little more stout than the sections of Fig. 1. The differences in stoutness are mere matters of design and obviously may 85 be varied as desired.

Whether the anchor bolts be passed through the ends of the core B, as shown in Fig. 1, or down through the central openings in the bases of the sections, the construction of the bolt may be the same. Commonly it comprises merely a screw-bolt or drive pin 17 which is anchored by a washer or cylinder 33 of lead. Ordinarily the pavement is drilled and the lead is set in place 90 in the drilled hole. Then the drive pin is driven down into the lead anchor or a screw-bolt is screwed into a nut contained in the same. These anchor-bolt arrangements are 95 common and need not be more fully described. An early example of an anchoring device applied to a pavement marker is shown in British Patent No. 265,803 of 1926.

100 Instead of securing the marker sections directly to the pavement as in the previous cases mentioned, the sections may be connected to a plate 34 as illustrated in Fig. 7. In such case the core 35, whether it be a long core such as the core B, or a short core such as the core 31, will be secured to the plate by a screw-bolt 36 which is threaded at its lower end into a threaded opening in the plate 34. The plate may hold a number of sections A or their equivalents or there may be an individual plate for each section, as desired. The forward edge of the plate is turned down as shown at 38 and the rear edge of the plate is similarly turned down as shown at 39. In this way the front and rear edges of the plate provide sharp edges 105 which bite into the pavement when the plate is laid on the pavement and subjected to use. With this construction it is not necessary to provide anchor bolt openings in the pavement, but the biting action of the plate will suffice to hold the marker in the desired 110 location.

115 Obviously sections A⁴, of uniform width like the sections A³, may be molded with an opening 40 for the passage of a bar B or the 120

like, and such sections may be assembled with spacing sections A⁵, similarly provided with core openings 42. These sections A⁴ and A⁵ may be alternately placed upon a bar B and the same effect will be obtained as 5 in the case of the sections A, where spacing sections are not used but the bases 10 are given a dimension lengthwise of the bar B greater than the face of the panel 11. The sections A⁴ and A⁵ may be secured to the 10 pavement through the bar B or they may be secured to the pavement directly as may be required by the circumstances or may seem best to the designer. The holes 19 may be used for this purpose, as heretofore described. 15

The section A⁴ is shaped somewhat differently from the previously described sections. This difference is found principally at the 20 point where the upper panel 44 joins the base 45. The lower end of the panel curves laterally at 46 into the upper part of the base 45, leaving a shoulder 47 along its lower edge, as clearly shown. All parts are molded together as one. When traffic from the left, 25 as viewed in Fig. 9, strikes the blade 44 it is pressed down into the dotted line position 48 at the right; when traffic from the opposite direction strikes down the blade 44 then it takes the position 49 shown in dotted lines at the left. 30

Obviously, the spacer sections A⁵ may be used with main panels of various shapes. The illustrated association of sections A⁴ and A⁵ is merely typical. 35

Again, the markers may in each instance consist of a single section and these sections may be strung along the highway in a straight or curved line and bear indications 40 upon them for the guidance of the traffic. Thus, instead of having a composite marker like that shown in Fig. 1 extending transversely of the direction of travel of the traffic, a number of separate sections bearing 45 the same guiding markings may be strung out in the direction of travel. In this case the word "stop" would be read by the on-coming drivers the same as if transversely arranged as in Fig. 1, but each letter would 50 be read as the driver approached it, the first being the letter "S" and the latter the letter "P". Obviously other arrangements might be made for the single section markers. What is here stated is merely suggestive. 55

From what has been said it will be seen 60 that our invention is capable of many alterations and modifications, those set forth being merely illustrative of what may be done in this direction without departing from the spirit and scope of our invention. We therefore do not wish to be limited to the particular adaptations and details of construction contained in the present disclosure but aim to cover all such changes and 65 uses as rightly come within the scope of our

invention by the terms of the appended claims.

What we claim as new and desire to secure by a patent of the United States is:

1. A traffic marker construction of the 70 class described, comprising a normally up-standing display portion of inherently flexible material and a base portion integral with and of the same material as said display portion and having a substantially 75 horizontal under surface for engaging the surface of the pavement, a core of metal in said base portion, and an anchor for engaging said core and securing the marker to the pavement. 80

2. A traffic marker construction of the 85 class described, comprising a plurality of marker units, each unit comprising a normally up-standing display portion of inherently flexible material and a base portion 90 integral with and of the same material as said display portion and having a substantially horizontal under face for engaging the surface of the pavement, a core of metal extending through the base portions of all 95 of said units, and a plurality of anchors for engaging said core and securing the complete marker, made up of said units, to the pavement. 100

3. A traffic marker construction of the 105 class described, comprising a unitary member of inherently flexible material consisting of a normally up-standing yielding display member and a relatively stout base lying forward of the display member and having 110 its forward edge sloping downward toward the traffic and its under face substantially horizontal to rest on the surface of the pavement, a metal core in said base, and anchoring means for engaging said core 115 to secure the marker to the pavement. 120

4. A traffic marker construction of the 125 class described, comprising a unitary member of inherently flexible material consisting of a normally up-standing yielding display member and a relatively stout base lying forward of the display member with 130 its upper surface sloping downward toward the traffic and its under surface substantially horizontal to rest on the surface of the pavement and having a transverse opening through it for the positioning of a core. 135

5. A traffic marker construction of the 140 class described, comprising a plurality of marker units, each unit comprising a normally up-standing yielding display member of inherently flexible material and a relatively stout base integral with and of the same material as said display member and extending forward of said member with 145 its forward edge sloping downward toward the traffic and its under face substantially horizontal to rest on the surface of the pavement and having a transverse opening through it for the placing of a core, the 150

openings of the marker units being aligned when said units are assembled side by side to compose the assembled structure.

6. A composite traffic marker of the class described, comprising a plurality of units, each unit comprising a normally upstanding yielding display member of inherently flexible material and a relatively stout base having a transverse opening through it, a bar extending through the said openings of a plurality of said units, and means for securing said bar to the pavement.

7. A traffic marker construction of the class described, comprising an integral unitary member of inherently flexible material throughout, consisting of a stout block-like base and a normally upstanding display blade, said base having an opening through it adapted to extend substantially horizontally when the marker is in service, said opening being provided for the passage of an anchoring core by which the base may be secured to the pavement, and said blade extending upward from the upper face of said base to serve as an indicating means to approaching traffic and being relatively thin in the direction of the traffic so as to flex readily relative to said base when pressed down by the wheels of traffic and to spring back by reason of its inherent resiliency once said wheels are past.

In witness whereof, we hereunto subscribe our names this 13th day of March, A. D. 1929.
